UNITED STATES PATENT OFFICE.

OLIVER W. WERNITZ, OF WARSAW, INDIANA.

WRENCH.

1,115,755.

Specification of Letters Patent.

Patented Nov. 3, 1914.

Application filed November 5, 1913. Serial No. 799,366.

To all whom it may concern:

Be it known that I, OLIVER W. WERNITZ, a citizen of the United States, residing at Warsaw, in the county of Kosciusko and State of Indiana, have invented certain new and useful Improvements in Wrenches, of which the following is a specification, reference being had to the accompanying drawings.

10 This invention relates to wrenches and more particularly to an improved pipe wrench, the invention having for its primary object to provide a wrench which may be easily and quickly applied to or removed 15 from the pipe and will securely retain its applied position in gripping engagement therewith.

The invention has for another and more specific object the provision of a wrench 20 including a handle having a jaw formed on one end, a complementary wrench jaw movable with relation to the first jaw, links connecting said jaws, and means for forcing the movable jaw into effective gripping engagement with a pipe when the wrench is 25 turned thereon.

The invention has for a further object to provide a wrench of the above character which is extremely simple in its construction, strong and durable and serviceable in 30 practical use and may be produced at small manufacturing cost.

With the above and other objects in view as will become apparent as the description 35 proceeds, the invention consists in certain constructions, combinations and arrangements of the parts that I shall hereinafter fully describe and claim.

For a full understanding of the invention, reference is to be had to the following 40 description and accompanying drawing, in which—

Figure 1 is a side elevation partly in section of a wrench constructed in accordance 45 with the present invention and showing the same applied to a pipe. Fig. 2 is a similar view of one end of the wrench showing the positions of the jaws when released from gripping engagement with the pipe; Fig. 3 50 is a section taken on the line 3—3 of Fig. 1.

Referring in detail to the drawing, 5 55 designates the main stationary jaw which is integrally formed upon one end of a suitable handle 6. One side of this handle is longitudinally recessed or cut away as shown at 7 for a purpose to be later re-

ferred to. The inner edge of the jaw 5 is provided with an obliquely inclined series of teeth or serrations 8 adapted for gripping engagement upon the periphery of a 60 pipe.

9 designates the complementary movable jaw which is provided with a shank 10. This jaw has also formed upon one face an inclined series of teeth or serrations 11, 65 which are opposed to the teeth 8 upon the stationary jaw 5. A pair of links 12 are disposed upon opposite sides of the wrench jaws and pivotally connected thereto as indicated at 13.

The inner end of the shank 10 terminates 70 in an angularly disposed portion 14 which is engaged in a recess or socket 15 provided in an enlargement 16 formed upon the wrench handle. The walls of this socket 75 are also inclined substantially in parallel relation to the angular end 14 of the shank.

As clearly shown in Fig. 1 of the drawings, when the wrench is applied to a pipe, the teeth of the jaws 5 and 9 are arranged 80 upon opposite sides of the pipe. Upon turning the wrench upon the pipe, the shank 10 moves longitudinally with relation to the handle 6 and as the angular end 14 of said shank rides upwardly upon the inclined 85 wall of the socket 15, the movable jaw 9 is tilted and forced inwardly upon the periphery of the pipe so that the teeth thereof will retain a secure gripping engagement upon the same. It will be obvious 90 that the greater pressure which is applied to the movable jaw will serve in gripping the teeth thereof more firmly upon the pipe. The links 12 are preferably curved 95 in the manner illustrated, so that said links tend to draw the movable jaw toward the stationary jaw, and thereby also lessen the strain on the links and the rivets 13. It will be obvious from the above statement 100 that only a very slight turn of the wrench upon the pipe is necessary to securely grip the jaws thereon. When it is desired to release the wrench from the pipe, the handle is simply moved for a short distance in the reverse direction so that an inward pressure is exerted upon the movable jaw 9 and the links 12 then act to spread or separate 105 the jaws and disengage the teeth thereof from the periphery of the pipe as clearly shown in Fig. 2, the angular end 14 of the shank 10 moving backwardly in the socket 15.

From the foregoing, it is believed that the construction and manner of use of my invention will be clearly and fully understood. Owing to the very few parts employed in the construction of the wrench, it will be obvious that the same is extremely strong and durable in practical use and may be produced at small manufacturing cost. The wrench is capable of easy and quick application to the pipe and may be conveniently employed in corners or other places where the ordinary pipe wrench cannot be used.

While I have shown and described the preferred construction and arrangement of the several parts of my invention, it will be understood that the same is susceptible of considerable modification and I therefore reserve the right to resort to all such legitimate changes as may be fairly embodied within the spirit and scope of the invention, as claimed.

Having thus described the invention, what is claimed is:

25 The herein described wrench comprising in combination the following elements to wit: a handle having a stationary jaw

formed on one end, said handle being provided upon one of its longitudinal edges intermediate of its ends with a housing, 30 said housing having internal obliquely inclined walls, a complementary jaw movable longitudinally with respect to the stationary jaw, said movable jaw being provided with a shank having an angularly disposed terminal extending within said housing and engaged upon one of the inclined walls thereof, and a pair of curved links pivotally connected at their ends to the respective jaws, said angular end of the shank of the 40 movable jaw coöperating with one of the obliquely inclined walls of said housing when the wrench is turned around a pipe to force said movable shank laterally from the handle and tilt the movable jaw between the links, whereby the same is moved toward the stationary jaw and into gripping engagement with the pipe.

In testimony whereof I hereunto affix my signature in the presence of two witnesses. 50

OLIVER W. WERNZT.
